UNITED STATES PATENT OFFICE.

SAMUEL R. WHEELER, OF DEXTER, MICHIGAN, ASSIGNOR OF ONE-HALF
TO F. H. KRAUSE, OF SAME PLACE.

DUMPING-CAR.

SPECIFICATION forming part of Letters Patent No. 254,182, dated February 28, 1882.

Application filed December 28, 1881. (No model.)

To all whom it may concern:

Be it known that I, SAMUEL R. WHEELER, of Dexter, in the county of Washtenaw and State of Michigan, have invented an Improvement in Dumping-Cars, of which the following is a specification.

The nature of this invention relates to certain new and useful improvements in the construction of cars especially designed for handling grain in elevators or grain store-houses; and the invention consists in the peculiar construction, arrangement, and various combinations of the parts, all as more fully hereinafter set forth.

15 Figure 1 is a perspective view of my improved dumping-car. Fig. 2 is a vertical central section.

In the accompanying drawings, which form part of this specification, A represents a suitable bed or body, which is designed to be mounted upon a suitable truck; but said truck forming no part of my invention, I do not deem it necessary to illustrate or describe the same in this connection. One side of this body or base A is cut away, forming the beveled edges a.

B represents a suitable box, which is pivotally secured in the upper portion of the section A, and is provided with a spring-catch, C, 30 upon its rear, which projects downward and engages with a stop, b, projecting from the rear wall of the body A, to secure and retain the box B in its level or horizontal position. The front of this box B is provided with a gate, D, 35 hinged thereto at its upper edge, while its lower edge is kept or retained in its closed position by means of the latches E, which are pivotally secured to proper hangers projecting downward from the bottom of the box B, or in any 40 other suitable manner which will cause the said latches to engage with the lower edge of the gate D when it is in its closed position, said latches being operated by springs or by weighting the inner ends thereof, so that they will positively engage by gravity. Beneath the inner 45 ends of these latches E, and laterally across the base A, upon the beveled side thereof, I secure a bar, F.

G is a rock-shaft, properly journaled or secured in suitable bearings at the rear of the 50 base A, and arranged in such a manner that said shaft may be partially turned, so as to cause its crank d to push the foot of the spring C outward and disengage the same from its stop b.

55 In practice we will suppose the device hereinabove described to be mounted upon a suitable truck designed to run upon proper tracks placed in a grain store-house, and wherein the grain is to be delivered into bins. This device, 60 with its truck, is loaded or filled with grain from the farmer's wagon or from an elevator, and it is then run up in front of the bin which is to receive the grain, at which point the crank-shaft is turned, so that the spring is released 65 from its engagement with its stop, and the car or the body B is then tipped toward the bin, rocking on its journal, and in its descent the inner ends of the latches E impinge against the rod F, which disengages said latches from 70 their engagement with the lower edge of the gate, and allows the weight of the grain to throw said gate open and discharge into the bin. After it is emptied the body B is then returned to its original position, when it is again ready 75 to receive another load.

What I claim as my invention, and desire to secure by Letters Patent, is—

1. In a dumping-car, a base having horizontal and inclined bearing-surfaces for the body 80 in its respective positions of rest and dump, combined with said body, having a hinged dumping-door, means for automatically opening and locking said door, and means for automatically securing the body in a horizontal position, as 85 specified.

2. The combination of the base A a, having stops F and notch b, with the body B, door D, weighted catch E, the spring-catch C, and crank-bar G d, all constructed, arranged, and 90 adapted to serve as and for the purposes specified.

SAMUEL R. WHEELER.
